D17077

UNITED STATES PATENT OFFICE.

HAMLET E. COLLINS, OF LAMBERTVILLE, NEW JERSEY, ASSIGNOR TO THE LAMBERTVILLE RUBBER COMPANY, OF SAME PLACE.

DESIGN FOR A RATTLE.

SPECIFICATION forming part of Design No. 17,077, dated February 1, 1887.

Application filed December 11, 1886. Serial No. 221,310. Term of patent 7 years.

To all whom it may concern:

Be it known that I, HAMLET E. COLLINS, a citizen of the United States, residing at Lambertville, in the county of Hunterdon and State 5 of New Jersey, have invented and produced a new and original Design for Rubber Toy Rattles or Whistles for Children, of which the following is a specification.

The object of this design is to provide a 10 novel and attractive india-rubber rattle or whistle for children; and it consists in a rubber egg-shaped body having a scalloped perforated disk at one side and the representation of the head of a chick extending from one end portion of the body.

The design is illustrated in the annexed drawings, in which Figure 1 is a side elevation of the rubber toy rattle or whistle; Fig. 2, a top plan view, and Fig. 3 a bottom plan view.

20 In the drawings, the numeral 1 indicates the

rubber egg-shaped body, 2 a scalloped perforated disk in one side thereof, and 3 the representation of the head of the chick extending from one end portion of the body. Around the neck of the chick extend scallops 4.

Having thus described my invention, what I claim is

The design for a toy rattle or whistle, consisting of the egg-shaped body having the scalloped perforated disk in one side and the representation of the head of a chick extending from the body, substantially as shown and described.

In testimony whereof I affix my signature in presence of two witnesses.

HAMLET E. COLLINS.

Witnesses:

W. A. GREENE,
EDUARD RITTENHOUSE.
